(57) **CLAIM**

The ornamental design for disinfection wipe dispenser device, as shown and described.

DESCRIPTION

FIG. 1 is an isometric top view of a of my new design in the closed configuration.

FIG. 2 is an isometric bottom view of a disinfection wipe dispenser device of my new design in the closed configuration.

FIG. 3 is a front view of a disinfection wipe dispenser device of my new design in the closed configuration.

FIG. 4 is a right side view of a disinfection wipe dispenser device of my new design in the closed configuration.

FIG. 5 is a rear view of a disinfection wipe dispenser device of my new design in the closed configuration.

FIG. 6 is a left side view of a disinfection wipe dispenser device of my new design in the closed configuration.

FIG. 7 is a top view of a disinfection wipe dispenser device of my new design in the closed configuration.

FIG. 8 is a bottom view of a disinfection wipe dispenser device of my new design in the closed configuration; and, FIG. 9 is a bottom a disinfection wipe dispenser device of my new design in the closed configuration attached to a beverage can.

The broken lines are included for the purpose of illustration of portions of the disinfection wipe dispenser device that form no part of the claimed design.

1 Claim, 4 Drawing Sheets
